United States Patent

Des. 234,630
Patented Mar. 25, 1975

234,630

MOTION PICTURE FILM CASSETTE

James M. Conner, Mamaroneck, N.Y., Henry J. Salvador, Whittier, Calif., and John F. Batter, Jr., Lincoln, Mass., assignors to Polaroid Corporation, Cambridge, Mass.

Continuation-in-part of design application Ser. No. 260,061, June 5, 1972. This application May 25, 1973, Ser. No. 364,153

Term of patent 14 years

Int. Cl. D16—99

U.S. Cl. D61—1 T

FIG. 1

FIG. 2

FIG. 3

FIG. 1 is a front perspective view of a motion picture film cassette showing our new design;

FIG. 2 is a rear perspective view thereof; and

FIG. 3 is a bottom plan view thereof.

This is a continuation-in-part of design application Ser. No. 260,061, filed June 5, 1972.

We claim:

The ornamental design for a motion picture film cassette, as shown and described.
